UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD HOLDER FOR WEFT-REPLENISHING LOOMS

Application filed November 24, 1928. Serial No. 321,672.

This invention relates to improvements in thread holders for weft replenishing looms and it is the general object of the invention to provide a clamp and tensioning device which may be caused to act in unison so that by a single operation the weaver may subject new threads to tension to take up slack and also clamp the threads in position.

In multicolor weft replenishing mechanisms it is customary to store the reserve bobbins in several vertical stacks and to lead the weft ends of the bobbins to a thread holder. As the bobbins descend toward transfer position the weft ends become slack and it is desirable to provide some means for taking-up this slackness. It is of course necessary to provide some means for holding the ends of the wefts and it is a further object of my present invention to provide a friction thread holding clamp and a weighted slack taking-up device which can both be moved to thread receiving position by a single operation on the part of the weaver.

In the form of thread holder shown in my prior Patent No. 1,674,861, I have shown a weighted hook which must be raised at the time a new supply of bobbins is inserted in the magazine so that the hook can act on the new threads. It is a further object of my present invention to actuate the thread clamp by the weighted hook as the latter is raised.

It is a more specific object of my present invention to provide a weft end retainer having a thread engaging element to be brought in frictional contact with a surface against which the weft threads are held by means of a yielding device which can be lifted when it is desired to establish a new relation between the weft ends and the clamp.

With these and other objects in view which will appear as the description proceeds, my invention relates in the combination and arrangement of parts hereinafter described and set forth in the claims.

In the accompanying drawings wherein a convenient embodiment of my invention is set forth,

Fig. 1 is a front elevation of a portion of a weft replenishing mechanism made according to my present invention,

Fig. 2 is an enlarged detailed top plan view taken in the direction of arrow 2, Fig. 1.

Fig. 3 is an enlarged end elevation taken in the direction of arrow 3, Fig. 1.

Fig. 4 is a vertical section on line 4—4 of Fig. 2, and

Fig. 5 is a detailed vertical section on line 5—5 of Fig. 2.

The magazine M is preferably of the multi-color type and has provision for storing reserve bobbins B in vertical stacks one of which is indicated at 10 in Fig. 1. The bobbins have thread ends 11 which must be held to a fixed point and which preferably should be acted upon by a slack taking-up or tensioning device. The magazine may be of the general form shown in prior Patent No. 1,030,748.

The frame of the magazine is provided with an arm 12 through which extends a rod 13 substantially parallel to the lay of the loom not shown and held in adjusted longitudinal position by a set screw 14. The outer end of the rod 13 is bent at right angles to extend in this instance rearwardly as at 15.

The thread controller indicated generally at T is mounted on the rear extension 15 and comprises a head 16 from which depends a guide section 17. There are extending vertically through the head 16 a plurality of cylindrical openings, shown in this instance as four and designated at 18. These holes 18 may if desired be staggered and arranged in parallel pairs as suggested in Fig. 2 to economize space.

Located in each of the openings 18 is a thread slack taking-up or tensioning element 19 having at its upper end a hook 20 and at its lower end a weighted cylindrical element 21 into which the hook extends and to which the latter is secured. The bores 18 extend downwardly through the guide portion 17 so that for all vertical positions within the thread controller T the weighted elements 21 will be guided. Stop rods 22 may extend across the bottom of the guide section 17 to prevent loss of the weights 21.

The matter thus far described except for the rod 13 and its manner of adjustment may

be substantially the same as shown in my aforesaid application and of itself forms no part of my present invention.

My present invention relates more particularly to the clamping means for the weft ends 11 and in carrying my invention into effect I provide the head 16 with a groove 40 which may extend substantially parallel to the extension 15 of the rod 13 and above the latter as shown in Fig. 4. The underside of the head 16 is provided with a plurality of bores 41 into each of which extends the lower end of a rod 42 the upper end of which is bent to extend horizontally as indicated at 43 in Fig. 3. The lower end of each of the rods 42 is provided with an enlarged cylinder 44 which fits into the corresponding bore 41. A compression spring 45 is located between the upper end of the bore 41 and the cylinder 44 and tends normally to hold the horizontal extension 43 in its lowest position, that is, seated in the groove 40 as shown in Fig. 4. The groove and extensions 43 are so proportioned that the latter will fit closely into the groove and hold any weft ends W which may be lie thereunder as suggested in Fig. 2.

The guide portion 14 is provided with a plurality of vertical slots 50 which extend transversely with respect to the extension 15 and there is one of these vertical slots for each bore 18, intersecting the latter centrally. Each weight 21 is provided with a lifting pin 51 which extends on the right and left hand sides, respectively, of the portions 17 as shown in Fig. 4. Each pin extends through one of the slots 50 and it is by this means that the hook 20 is held in the proper plane to effect ready threading when new bobbins are being put into the magazine.

As shown in Fig. 4 the left hand end of each pin is extended as at Fig. 2 to lie under the corresponding cylinder 44. The slots 50 in addition to determining the plane of the hooks 20 also require the extension 52 to remain in alignment with its corresponding cylinder 44. The rods 42 may extend through the extension 15 if desired and the thread controlling device T may be held to said extension by means of set screws 53.

In operation when new bobbins are to be added to the magazine the weft ends will be drawn to the left as shown in Fig. 1 and the operator will lift the pin 51 which will of course cause a corresponding upward movement of the weight 21 and the corresponding hook 20 until the latter lies above the top surface of the head 16. The distance between the extension 52 and the corresponding cylinder 44 is such that when the hook 20 is in the position shown in Fig. 5 the lifting rod 51 and the rod 42 corresponding thereto will be in the dotted line position shown in Fig. 4. It will therefore be possible by a single upward movement of rod 51 on the part of

the operator to lift both the tensioning slack taking-up hook 20 and also the clamping arm 43. After the weft ends have been caught under the clamping arm the pin 51 will be lowered to stress the new threads.

It is desirable to have the parts so proportioned that the clamping arm 43 will hold the thread tightly in the groove 40 before the corresponding hook 20 has been lowered to a position where it can stress the warp threads, that is, in the downward movement of the lifting pin 51 the clamping arm 43 strikes the thread and holds it in position before the hook 20 is able to tension the threads. This result is accomplished by having the distance between the extended end 52 of pin 51 and the corresponding cylinder 44 greater than the distance between the associated hook 20 and the top surface of the head 16, as shown clearly in Fig. 4.

From the foregoing it will be seen that I have provided clamping and tensioning means for the weft ends of reserve bobbins, both of the devices being under a single control so that the operator may use one hand to hold the weft ends in the other hand to place the thread controller in a condition to receive the threads. It will further be seen that in the sequence of operations the clamp will engage the thread and hold the same securely in the slot 40 before the tensioning elements engage the thread. While I have shown in rods 42 as extending through the rearwardly extending end of the supporting bar 13 yet I do not wish to be limited to this construction as it is sufficient if the said rods 42 are free to move up and down with respect to the head 16 and the latter is supported by the bar.

Having thus described my invention it will be seen that changes and modifications may be made therein by those skilled in the art without departing from the spirit and scope of the invention and I do not wish to be limited to the details herein disclosed, but what I claim is:

1. In a thread holding and tensioning device for a weft replenishing loom having a supply of weft bobbins from each of which extends a weft end, a thread tensioning element for the weft ends, a thread clamping element for the weft ends, said tensioning element being intermediate the weft supply and clamping element, and means to move the clamping element to thread releasing position when the tensioning element is moved to a position to receive a new weft.

2. In a thread holding and tensioning device for a weft replenishing loom having a supply of weft bobbins from each of which extends a weft end, a tensioning element for the weft ends, a clamping element for the weft ends, said tensioning element being intermediate the weft supply and clamping element, and connections to be established between said

elements when the tensioning element moves to a position to receive fresh weft ends to automatically move the clamping element also to a position to receive fresh weft ends.

5. In a thread holding and tensioning device for a weft replenishing loom having a supply of weft bobbins from each of which extends a weft end, a tensioning element for the weft ends, a clamping element to hold the weft ends, said tensioning element being intermediate the weft supply and clamping element, and means operative from a single point of control to move both of said elements to weft end receiving position.

15. In a thread holding and tensioning device for a weft replenishing loom having a supply of weft bobbins from each of which extends a weft end, a fixed frame, a thread tensioning element movable in the frame, a thread clamping element movable in the frame and cooperating with the latter to hold weft ends, and means operative from a single point of control to move both of said elements relatively to the frame to a position 25 to receive fresh weft ends.

25. In a thread holding and tensioning device for a weft replenishing loom having a supply of weft bobbins from each of which extends a weft end, a frame, a hooked thread 30 tensioning member slidable in the frame, a thread clamping member also slidable in the frame, said elements normally being in positions incapable of receiving fresh weft ends, and means to connect said elements operatively together so that movement of one of them to thread receiving position will cause movement of the other to thread receiving position.

35. In a thread holding and tensioning device for a weft replenishing loom having a supply of weft bobbins from each of which extends a weft end, a thread clamping element for the weft ends, a thread tensioning element for the weft ends, one of said elements being normally out of thread receiving position and connections between said elements whereby movement of one of said elements to thread receiving position will cause movement of the other elements also to thread 45 receiving position.

45. In a thread holding and tensioning device for a weft replenishing loom having a supply of weft bobbins from each of which extends a weft end, a fixed member, a thread 55 tensioning element slidable in and normally housed within the member, a thread clamping element slidable in the member and normally cooperating with the latter to clamp weft ends, both of said elements normally being incapable of receiving new weft ends, and a single control member for moving both of said elements relatively to the member to weft end receiving position.

55. In a thread holding and tensioning device for a weft replenishing loom having a

supply of weft bobbins from each of which extends a weft end, a fixed member having an upwardly extending face, a thread tensioning element movable within the member by gravity and tending to move away from said face of the member, a clamping element movably mounted on the member and cooperating with the latter normally to hold weft ends, and means to operatively connect said elements so that when one of them is moved to thread receiving position in a direction transverse of said face the other of said elements will automatically be moved to thread receiving position.

70. 9. In a thread holding and tensioning device for a weft replenishing loom having a supply of weft bobbins from each of which extends a weft end, a fixed member having an opening therein across which weft ends may extend, a tensioning element movable in said opening to engage weft ends to cooperate with said member to tension said ends, a clamping element supported by and movable with respect to the member and cooperating with the latter to hold the weft ends, and means to establish operative connection between said elements when one of them is being moved to thread receiving position in a direction toward the surface of the member to cause movement of the other element to 95 thread receiving position.

10. In a thread holding and tensioning device for a weft replenishing loom having a supply of weft bobbins from each of which extends a weft end, a member having a pair of substantially parallel bores therein, a tensioning element located in one of the bores and capable of cooperating with said member to tension the weft ends, a clamping element movable in the other bore and cooperating 100 normally with the member to hold the weft ends, and means to operatively connect said elements so that movement of one of them toward thread receiving position will move the other element also to thread receiving 110 position.

11. In a thread holding and tensioning device for a weft replenishing loom having a supply of weft bobbins from each of which extends a weft end, a member having a pair 115 of substantially vertical parallel bores therein, a thread tensioning element actuated by gravity and movable in one of said bores and cooperating with the member to tension the weft ends, a thread clamping element movable in the other bore and normally cooperating with the member to hold the weft ends, both of said elements normally being incapable of receiving fresh weft ends, and means to establish operative connection between said 120 elements so that when one of the latter is moved to thread receiving position the other element will also be moved automatically to thread receiving position.

12. In a thread holding and tensioning de- 125

vice for a weft replenishing loom having a supply of weft bobbins from each of which extends a weft end, a thread tensioning element capable of a comparatively large movement to take up slack in the weft ends, a thread clamping element to be given a comparatively small movement to receive fresh ends and release old ends, and a lost motion connection between said elements operative during the latter part of the movement of the tensioning element toward position to receive a fresh weft end to cause the clamping element to move to releasing position to receive fresh weft ends.

13. In a thread holding and tensioning device for a weft replenishing loom having a supply of weft bobbins from each of which extends a weft end, a member having a pair of parallel bores therein, a clamping element movable in one of said bores and normally cooperating with the member to hold the weft ends, a tensioning element movable in the other bore and cooperating with the member to take up slack in the weft ends, a pin carried by one of the elements and positioned for engagement with the other element, and guide means formed on the member to cause the pin to move into engagement with one of the elements when the element carrying the pin is moved.

14. In a thread holding and tensioning device for a weft replenishing loom having a supply of weft bobbins from each of which extends a weft end, a member having an upper face in which there is an opening across which the weft ends may extend, a tensioning element having a portion to engage weft ends and cooperate with said upper surface of the member to take up slack in the weft ends, a clamping element cooperating with the member to hold the weft ends, and a device carried by the tensioning element to engage the clamping element to move the latter to releasing position when the tensioning element is moved toward the aforesaid surface of the member, the distance between the device and the clamping element normally being greater than the distance between the portion of the tensioning element which engages the weft end and the aforesaid surface of the member.

15. In a thread holding and tensioning device for a weft replenishing loom having a supply of weft bobbins from each of which extends a weft end, a weft tensioning element to take up slack in the weft ends, a weft clamping element to hold the weft ends, said elements normally being in position incapable of receiving fresh weft ends, and means to move said elements to thread receiving position in such order that the tensioning element is in position to receive fresh weft ends before the clamping element is in such position.

16. In a thread holding and tensioning de-

vice for a weft replenishing loom having a supply of weft bobbins from each of which extends a weft end, a tensioning element for weft ends to take up slack in the latter, a clamping element to hold the weft ends, said tensioning element being intermediate the weft supply and clamping element, means to move said elements to thread receiving position, and means whereby the clamping element will operate to clamp the weft ends before the tensioning element is capable of tensioning the weft ends.

17. In a thread holding and tensioning device for a weft replenishing loom having a supply of weft bobbins from each of which extends a weft end, a tensioning element to take up slack in the weft ends, a clamping element to hold the weft ends, said elements normally being in a position incapable to receive weft ends but capable of movement together toward a position to receive fresh weft ends, and means establishing connections between said elements so proportioned that when said elements move from thread receiving position to normal position the clamping element will become operative to hold the weft ends before the tensioning element operates to take up slack.

In testimony whereof I have hereunto affixed my signature.

ALBERT A. GORDON.
